UNITED STATES PATENT OFFICE.

LOUIS GODDU, OF BOSTON, MASSACHUSETTS, ASSIGNOR TO HENRY E. TOWNSEND, OF SAME PLACE.

IMPROVEMENT IN MACHINES FOR NAILING SHOE-SOLES, &c.

Specification forming part of Letters Patent No. 122,377, dated January 2, 1872.

To all persons to whom these presents may come:

Be it known that I, LOUIS GODDU, a citizen of the Dominion of Canada, but temporarily residing at Boston, of the county of Suffolk and State of Massachusetts, have made a new and useful Invention or Improvements in Machinery for Nailing Shoe-Soles or various other articles with wire; and do hereby declare the same to be fully described in the following specification and represented in the accompanying drawing, of which—

Figure 1 is a front elevation; Fig. 2, a side view; and Fig. 3, a longitudinal section of the head of a nailing-machine with my improvements or invention.

Such other figures or drawings as may be necessary to a full or proper illustration of my invention will be hereinafter referred to and described.

The machine exhibited by the said drawing contains the main essential elements of a nailing-machine, they consisting of a guide-nose, a nail-driver and its operative mechanism, a mechanism for feeding in the wire from which each nail is to be severed, a mechanism for receiving the wire and transferring the nail portion thereof to the guide-nose passage, and, finally, a mechanism for severing a nail from the wire.

The special object for which the present machine is designed is the fixing of soles or welts in place by a few nails preparatory to their being regularly pegged or nailed to the upper of the shoe; an attendant presenting, as may be required, the lasted shoe to the nose-piece of the machine, and at the same time operating the pedal of the machine by his foot, so as to put the machine in operation and cause it to drive a nail through such part of the sole or welt and into the last where it may be desirable to have one inserted. My present improvements may be said to consist as follows, viz.: In certain mechanism, as hereinafter described, for regulating the feeding forward of the wire; also mechanism for actuating the main shaft of the machine and holding it at rest under circumstances as hereinafter explained.

A denotes the stock, head, or frame for supporting the operative parts, it terminating in or being provided with the guide-nose B, which

has a vertical passage, a, leading down through it. Through this passage the nail, after being severed from the wire, is driven or forced by the nail-driver, shown at c. The said nail-driver is fixed in the lower part of a carrier or vertical slide-rod, C, arranged in the frame or stock A, and provided with a spring, D; the purpose of which is to depress the carrier after each elevation of it, such depression being with power sufficient to cause the nail-driver to force the nail into the article into which it may be required to be driven. Within the frame or stock A, and disposed therein, as represented, is the main shaft E, carrying a pinion, F. This pinion engages with a gear, d, arranged on a stationary arbor, e. There is fixed to the gear d, on one side of it, a ratchet-wheel, f, (see Fig. 4, which is a side view of the ratchet and gear,) with which a draw-pawl, g, applied to one side of a wheel, h, and provided with an actuating-spring, s³, operates. The wheel h turns freely on the said arbor, and while in operation is to have a reciprocating rotary motion, such being to be effected by a pedal connected with the wheel by a rod, i, pivoted to the two, a spring being used to elevate the pedal and rod. An entire revolution is to be imparted to the shaft E during each downward movement of the pedal. A cam-wheel, k, shown in side view in Fig. 5, receives in its cam-groove l a friction-roller projecting from one side of an arm, m, such arm being extended upward from a shaft, n, to whose front end the transerrer L is fixed, the latter deriving its motions from the said shaft, arms, and cam. Furthermore, there is fixed on the shaft E, at its front end, a cam or wiper, O, whose purpose is to effect the elevation of the nail-driver carrier C at the proper times and to allow it to be driven downward by the spring D. The wire from which the nails are to be successively cut is to be led through a passage, w, of a guide, I, and thence against the milled or toothed periphery of a feed-wheel, K; thence through a conduit, v, to and past the cutting-edge of the stationary cutter x, arranged as shown. From thence the wire passes into the passage z of the transerrer L. The said transerrer carries a cutter, y, which, operating in conjunction with the stationary cutter x, serves, at the proper period, to sever a

nail from the wire. By the movements of the transferer *L* the wire will be cut or the nail will be severed from it by the cutters, and subsequently will be moved directly over the guide-nose passage *a*, ready for being driven by the nail driver. There is applied to the periphery of the cam-wheel *k* a friction-brake or presser, *a*², which, arranged in the frame, as shown, has a spring, *b*², for forcing it downward, the elastic force or pressure of the spring being increased or diminished by a screw, *c*², screwed into the frame or head *A* and against the upper end of the spring. This friction-brake is to prevent the cam-wheel from being revolved by its momentum beyond what may be necessary for its successful action. The brake *a*² is also to hold the shaft *E* from revolving while the pawl-carrying wheel *h* is being moved backward so as to slip the pawl *g* over the ratchet-wheel *f*. The feed-wheel *K* revolves on an arbor, *k*', projecting from the head *A*. A ratchet or pawl, *l*', carried by an arm, *m*', and arranged with the toothed periphery of the feed-wheel, in manner as shown, operates such wheel. The arm *m*' projects from a shaft, *n*', which extends through the arbor *k*'. From the rear end of such shaft *n*' an arm, *o*', is extended, and carries a friction-wheel, *p*', to act against the periphery of a cam, *q*', fixed on the outer side of the cam-wheel *k*, the shape of the cam *q*' being shown in Fig. 6. There is connected to the arm *o*' a spring, *r*', which is fastened to a projection, *s*', from the frame or head *A*, all being arranged as shown. This spring draws the friction-roller closely up to the cam. Fig. 7 is a horizontal section taken through the axis of the shaft *n*' and the parts adjacent and in the vicinity of such shaft. There projects back from the frame *A*, and concentric with the shaft *n*', a tubular arbor, *t*', which constitutes the fulcrum of a stop-lever, *R*, a top view of such lever being given in Fig. 8 and a side view of it in Fig. 9. From the shorter arm *u*' of such lever a stud, *v*', is extended against the inner edge of the arm *o*'. The arm *w*' of the stop-lever *R* is hollow or chambered to re-

ceive a spring, *x*', which is held in place in the arm by a screw, *y*', screwed therein and against the outer end of the spring. The inner end of the spring bears against the arbor *t*'. From the said lever an arm, *z*', extends, in manner as shown, between the inner ends of two screws or adjustable stops, *a*³ *b*³, arranged in the frame *A*, in manner as represented. The purpose of the stop-lever *R* and its adjustable stops *a*³ *b*³ is to regulate the extent of movement of the arm *o*' toward the cam *q*', and, as a consequence, the feeding of the wire in order to cause the nail cut off and driven to have any desirable length.

By taking hold of the arm *u*' of the lever *R* an attendant will be able to move the stop-lever between its stops more or less, as may be requisite, to vary the feed of the wire, the spring of the lever sufficing to hold, by friction, the lever in the position in which it may be so placed.

In the above-described machine, what I claim as my invention may be stated as follows—that is to say:

I claim the combination and arrangement of the stop-lever *R*, the adjustable stops *a*³ *b*³, the feed-wheel *K*, the pawl *l*', the arm *m*', the shaft *n*', the arm *o*', the spring *r*', the roller *p*', and the cam *q*', all being constructed and applied together, substantially in manner and to operate as described.

Also, the combination therewith of the spring *x*', or such, and the adjusting-screw *y*', arranged in the stop-lever, as set forth.

Also, the friction-brake *a*² and its spring *b*² and screws *c*², in combination with the gears *F* *d*, ratchet-wheel *f*, and reciprocating pawl *g* and its carrier *h* applied to the shaft *E*, and with the cam-wheel *k* of the mechanisms, as described, for operating the transferer and feed-wheel.

LOUIS GODDU.
